UNITED STATES PATENT OFFICE

2,278,803

PLASTERER'S FLOAT AND TROWEL

Edward Stabbert, Tacoma, Wash.

Application January 18, 1940, Serial No. 314,397

1 Claim. (Cl. 72—136)

The present invention relates to improvements in plasterers' floats and trowels, and constitutes an improvement upon the float disclosed in my co-pending application, Serial Number 209,434 filed May 23, 1938.

The said pending application pertains to and covers a form of trowel having a perfectly flat steel base with an integral flange extended along one side margin perpendicularly to the base, the said flange comprising straight end portions meeting centrally in a slight, outstanding obtuse angle, for the purposes stated in that application.

While the trowel of that application serves well its intended purpose, it is necessary to construct the same of thin and somewhat flexible steel in order that the free or unflanged side have the desired degree of flexibility in use, so as not to scuff or scrape the surface of the work. This thinness of material makes it necessary in turn to brace the side or angle flange from the handle, as shown in the other application.

Moreover, in the use of such single flanged or "single wing" angle trowel, it becomes necessary for the plasterer in working from one side of a room to the other, to lay his trowel upon the hawk in order to reverse it for use at the opposite corners, this constituting an objection to the use of that form of trowel, in the mind of some operators.

It is the prime purpose of the present invention therefore to provide a form of trowel overcoming the foregoing objections to the form of trowel presented in the co-pending application, while preserving its advantages.

Another object is to provide a trowel or float made of an oblong piece of sheet steel or other suitable material, of such thickness as to be substantially inflexible and resistant to strain without bracing, dimensioned to the desired size, having opposed side wings or angle flanges turned upwardly along both sides of the base or blade of the tool, the base itself being slightly convexed, transversely on its under or working face to prevent scuffing of the work, the side flanges being turned slightly outward for the same purpose and to facilitate angle work, and having a suitable handle mounted at its upper side.

With the foregoing objects in view, with such other objects and advantages as may appear from the specification, a preferred embodiment of the invention is disclosed in the accompanying drawing as a part of the specification, and wherein:

Figure 1 is a top perspective view of a trowel or float embodying my improvements.

Figure 2 is an enlarged cross section on the line 2—2 of Figure 1.

Figure 3 is a plan view of one end of a modified form of trowel, showing the base and side wings slightly drawn in or tapered.

The trowel as made in accordance with my invention and represented generally at 5 in the drawing, comprises a rectangular blade, base or work plate 6 and opposed side flanges or angle wings 7 turned upwardly along the sides of the base. The base and flanges are preferably formed integrally of a single piece of sheet steel or other suitable material. However the flanges may be separately formed and attached if desired, and in any event they are preferably beveled off at their outer ends, as shown at 8 to facilitate use of the tool. A conventional or any desired form of handle 9 is medially mounted on the upper face of the base or blade 6, by means of screws 10 passed up through the base into the ends of the handle, the heads of the screws being counter-sunk flushly into the under or working face of the base, as shown at 12. The whole tool is of course of conventional or any desired size, and is usually oblong as to the base.

In accordance with my invention the base or blade 6 and flanges 7 are as stated formed of sheet steel or other suitable material, and of such thickness or temper as to be relatively stiff and inflexible against pressure or strain. The under or working face of the base 6 is slightly arcuate, arched or convexed transversely of its long axis, as indicated at 6a in Figure 2, in comparison with the straight dotted line 13. The side flanges or angle wings 7 are turned or tipped slightly outward from the base, as indicated at 7a, in comparison with the dotted line 14 extended perpendicularly to the line 13, as shown at the right angle 15. Of course, if made of uniform sheet material, the upper side of the base would be correspondingly arcuate or concaved, as indicated at 6b in comparison with the dotted line 16 extending parallel with the line 13. This curve of the upper side of the blade is a structural result however, and is relatively unimportant.

If desired the ends of the base 6 at the under face may be beveled off slightly, or the ends 50 slightly upturned as indicated at 6c, to prevent scuffing the work on endwise movement of the tool. Also the ends of the tool, including the base 6 and wings 7, may be slightly drawn in or tapered as shown at 7a in Figure 3, for the same purpose.

Also if preferred, the base, blade or plate 6, as well as the side wings or flanges 7, might be formed of thinner and more flexible material, and then the flanges braced to the handle in a manner pointed out in my said co-pending application, it not being thought necessary to reproduce that showing here.

In use and by virtue of the two wings or flanges, one at either side of the tool, the trowel may be worked from one side of a room to the other and into the corners at each side, without the workman having to reverse it. The convexed working face of the base or blade enables it to be smoothly drawn or floated over the wall being plastered, without scuffing or gouging the surface of the work. The outward tip of the side wings or flanges with their beveled ends or corners enables the tool to be smoothly and efficiently and smoothly operated in the wall or ceiling corners

and angles, and to shape these corners correctly, without scraping, gouging or roughening the work, as will be readily understood by those skilled in this art.

While I have here shown and described a particular embodiment of the invention, and have described specific structural features thereof, the same may be changed or modified as found desirable, within the scope of the claim.

I claim:

In a trowel, an oblong work blade slightly arched across its working face on its narrow dimension, the extremities of the base being slightly upturned and tapered inwardly at the sides to prevent scuffing the work, and flanges extended angularly upward and outward along the two opposite straight sides of the base, the ends of the flanges being beveled off to facilitate working in corners.

EDWARD STABBERT.
